DESIGN FOR A PEA SHELLER

Gerald N. Coughlan, East Orange, N. J.

Application November 7, 1935, Serial No. 59,423

Term of patent 7 years

To all whom it may concern:

Be it known that I, Gerald N. Coughlan, a citizen of the Irish Free State and a resident of East Orange, county of Essex, and State of New Jersey, have invented a new, original, and ornamental Design for a Pea Sheller, of which the following is a specification, reference being had to the accompanying drawing, forming a part thereof.

Fig. 1 shows a front elevation of a pea sheller embodying my design;

Fig. 2 shows a side view of same; and

Fig. 3 shows a rear elevation of same.

I claim:

The ornamental design for a pea sheller as shown.

GERALD N. COUGHLAN.
